UNITED STATES PATENT OFFICE

93,723

DESIGN FOR A DISH OR SIMILAR ARTICLE

Otto Keitel, Selb, Germany, assignor to Oneida Community, Limited, Oneida, N. Y., a corporation of New York

Application April 11, 1934, Serial No. 51,378

Term of patent 14 years

To all whom it may concern:

Be it known that I, OTTO KEITEL, a citizen of the Republic of Germany, residing at Selb, Bavaria, have invented a new, original, and ornamental Design for a Dish or Similar Article, of which the following is a specification, reference being had to the accompanying drawing, forming a part thereof, said drawing being a plan view of a dish showing my new design, the essential feature of which is the ornamentation on the rim of the dish.

I claim:

The ornamental design for a dish or similar article as shown and described.

In testimony whereof I have hereunto set my hand.

OTTO KEITEL.
